(57) **CLAIM**

The ornamental design for a welder's helmet, as shown and described.

DESCRIPTION

FIG. 1 is a perspective view of a welder's helmet showing my new design;

FIG. 2 is a side view;

FIG. 3 is a top view;

FIG. 4 is a front view;

FIG. 5 is a rear view; and,

FIG. 6 is a bottom view.

In the drawings, the broken lines represent environment and form no part of the claimed design.
